[57] CLAIM

The ornamental design for a portable, battery-operated,

DESCRIPTION

FIG. 1 is a rear and upper right perspective view of a portable, battery-powered, rechargeable, electrical power supply pack for a computer video game showing my new design;

FIG. 2 is a perspective view from below of my design shown in FIG. 1 in a battery recharging position. The cable has been omitted for convenience of illustration; FIG. 3 is a bottom plan view of the design in FIG. 1. The cable has been omitted for convenience of illustration;

FIG. 4 is a right side elevational view thereof; FIG. 5 is a top plan view of the design of FIG. 1. The cable has been omitted for convenience of illustration; FIG. 6 is a side plan view of the other side of the design of FIG. 1. The cable has been omitted for convenience of illustration;

FIG. 7 is an end plan view of the design of FIG. 1, the other end plan view being the same. The cable has been omitted for convenience of illustration; and,

FIG. 8 is a front and upper right perspective view thereof shown in use. The broken line showing of the computer video game apparatus is included for the purpose of illustrating environmental elements only and forms no part of the claimed design.

FIG. 5

FIG. 6

FIG. 7

FIG. 8
